BALANCED PANIC DOOR

Edmund Peremi, Bayside, and Henry Weimann, Yonkers, N. Y., assignors, by mesne assignments, to General Bronze Corporation, Garden City, N. Y., a corporation of New York

Application January 27, 1945, Serial No. 574,842

4 Claims. (Cl. 20—16)

1

This invention relates to a door construction. An object of the invention resides in the creation of a door which is so constructed and mounted in a doorway that, when force is applied adjacent one of its stiles, the door will have a pivotal movement and a movement of translation toward one of the door jambs to extend both inwardly and outwardly of the doorway adjacent one jamb thereof, and when force is applied adjacent both stiles of the door on one face thereof, the door will swing on a single pivot to extend outwardly of and entirely clear of the doorway.

A further object of the invention resides in the provision of a door of the character above referred to, in which the construction is simple, sturdy and easily installed and maintained, and in which the operating and control mechanisms are concealed within the door and the doorway structures and in which the mechanical closing device for the door is located in the floor beneath the door.

With these and other objects in view that will be pointed out as this description progresses, the invention consists in the combination and arrangement of parts described in the specification and set forth in the claims, but it is to be understood that details of construction may be varied within the skill of the art without departing from the spirit of the invention or exceeding the scope of the claims.

In the drawings:

Figure 1 is an elevation of a door constructed in accordance with our invention;

Figure 2 is a vertical sectional view of a portion of the door construction at the top of the door;

Figure 3 is a vertical transverse section on line 3—3 of Figure 2;

Figure 4 is a vertical transverse section on the line 4—4 of Figure 2;

Figure 5 is a vertical transverse section on the line 5—5 of Figure 2;

Figure 6 is a horizontal section on the line 6—6 of Figure 2;

Figure 7 is a horizontal section on the line 7—7 of Figure 2;

Figure 8 is a vertical section of the bottom of the door construction;

Figure 9 is a section on the line 9—9 of Figure 3;

Figure 10 is a section on the line 10—10 of Figure 8;

Figure 11 is a section on line 11—11 of Figure 3;

Figure 12 is a section on line 12—12 of Figure 1;

Figure 13 is a view showing the door in its closed position;

Figure 14 shows the door partly swung in its

2

pivotal movement and in its movement of translation as a balanced door;

Figure 15 is a similar view showing the door after it has completed its movement toward the jamb;

Figure 16 shows the door swung as a panic door wherein it swings about a single pivot as a hinge, the dotted lines indicating the progress of the door from its closed toward its open position; and

10 Figure 17 is a horizontal sectional view, partly in elevation, of a floor type door check that may be used in our invention.

The invention will be described in connection with a single door, but it is of course to be understood that a series of doors may be arranged contiguous to each other in a manner that is now common in the general art. In Figures 1 and 13 one of such doors is shown and a second indicated.

20 In the embodiments of the invention illustrated in the drawings the door, which includes upper and lower rails 1 and 2, and side stiles 3 and 4, is mounted in a doorway which is defined by the jambs 5 and 6, the head 7 and the floor 8.

25 The jamb 5, as shown in Figure 12, may be made in separate pieces for convenience of production and is hollow from end to end. Within the jamb 5 a coordinating element 9 is located. This coordinating element includes a rod which 30 extends vertically within the jamb 5 and is preferably at least for a portion of its length of tubular form and acts as a main vertical pivot member. A supporting arm 10 is preferably rigid with the coordinating element 9 at its upper end, as indicated at 9', and a similar arm 11 is preferably rigid with the coordinating element at its lower end, as indicated at 9''.

Reference to Figure 7 of the drawings will disclose that the end 12' of each of these arms is 40 designed to conform to the contour of the adjacent door jamb so that the appearance of the jamb at its upper and lower ends where it is cut away to accommodate the arms 10 and 11 will conform to that of the intervening portion.

45 The lower arm 11 is provided with a socket in which the rotatable lug 12 of a floor type door check, indicated as a whole by the reference numeral 13, is secured by a set screw 14. This door check that we have illustrated includes a casing 13a that may be set in the floor of the doorway in any suitable manner. An arm 13b is pivoted to an ear 13c that is rigid with the lug 12 and is connected by links 13d and 13e to a winding plate 13f of a coil spring 13g. This coil spring is 50 mounted within the casing 13a in such manner

that the spring may be put under such initial tension as is desired. Arms 13*h* and 13*i* are rigid with the lug 12 and have links 13*j* and 13*k* pivotally connected thereto. These links 13*j* and 13*k* are pivoted to pistons 13*m* and 13*n* that operate within the cylinders 13*o* and 13*p* which cylinders are held rigidly within the casing 13*a* by any suitable means and which cylinders are provided with openings 13*q* through which the air may leak as the pistons approach their closed ends.

Thus, when the door is moved as a balanced door into the position illustrated in Figure 15, the lug 12 will be moved in a counter clockwise direction. This movement of the lug will wind the spring 13*g* through the linkage connection thereto and place the spring under tension so that when the door is released the spring will operate to return the door to its initial or closed position.

Moreover, when the door is moved to an open position as a balanced door, the piston 13*m* will move outwardly in its cylinder, while the piston 13*n* will move inwardly in its cylinder, and when the door is moved to its initial or closed position by the spring 13*g* the pistons will have the reverse movements. Thus the movements of the door as a balanced door will be cushioned as the door approaches its open and closed positions.

When the door is moved as a panic door, as for instance into the position shown in Figure 16, the lug 12 will move in a clockwise direction. At this time the spring 13*g* will be placed under no tension and therefore will not tend to close the door.

However, to insure the door remaining open we form a seat 13*r* in the piston 13*n* which seat cooperates with a ball 13*s* which is pressed, by means of a spring 13*t*, into engagement with the seat when the piston reaches its outermost position, as it does when the door reaches its open position as a panic door. The pressure exerted by this spring 13*t*, however, is such that it may easily be overcome by a pull on the door when it is desired to restore the door to its initial or closed position.

Furthermore, the operations of the pistons in their cylinders will cushion the movements of the door as it approaches its open and closed positions when operating as a panic door.

A pivot pin 15 is slidably mounted within the opening at the upper end of the coordinating element 9. Set screws 16 pass through the coordinating element 9 and are adapted to engage the pivot pin to secure it to the coordinating element. A set screw 17, that passes through the pivot pin and has threaded engagement with the coordinating element at the two points indicated in Figure 2 of the drawings, cooperates with the set screws 16 to hold the pivot pin 15 and the coordinating element together as a rigid unit. It may, however, be backed off from its screw threaded engagement with the coordinating element to slide within the slot 18 to permit the movement of the pivot pin within the coordinating element when the set screws 16 are disengaged from the pivot pin, but to limit the movement of the pivot pin within the coordinating element by its engagement with the bottom of the slot 18.

The upper end of the pivot pin is mounted in a thrust and lateral bearing 19 that is carried by a bracket 20 on the adjacent wall. The pivot pin 15 is screw threaded at its upper end and is provided with a nut 21 between which and the bearing 19 a washer is interposed.

Thus when the set screws are engaged with the

pivot pin the nut may be operated to raise or lower the door for adjustment, and when the set screws 16 are disengaged, the set screw 17 loosened and the nut 21 removed, the pin may be dropped down in the recess of the coordinating element 9 to a point below the head of the doorway. Thus the upper end of the door may be swung outwardly and the door removed from the lug 12 of the door stop and thus from the doorway.

Referring to Figures 12 and 16 particularly, it will be noted that the edge of the door stile 3 adjacent the jamb 5 recedes and may be formed as an arc 22 whose center is the vertical center of the coordinating element 9, to permit the door to clear the jamb in its movements to open and closed positions. Thus when the door is moved about the coordinating element only, as a pivot, the door will clear the jamb 5 as the door moves outwardly in a simple swinging movement about the center of the coordinating element 9 as its only pivot, and may assume the position shown in Figure 16 where it extends entirely beyond the doorway area so that the latter is entirely free from the door frame.

A suitable weather stripping 23 may be carried by the door to seal the space between the jamb 5 and the edge of the stile 3 when the door is in a closed position, this weather stripping being flexible to permit its passage around the door jamb.

The upper and lower rails of the door are provided with recesses 24 and 25, which open through the outer face of the door but are closed by the abutment facings 26 and 27 of the upper and lower rails. These pins 28 and 29 act as supporting arm pivot members 34. These recesses are of sufficient depth to permit the arms 10 and 11 to lie flush with the outer face of the rails so as to impart a finished appearance to the rails.

The arms 10 and 11 are pivotally connected by pins 28 and 29 to the upper and lower rails 1 and 2 respectively, which pass through ears 30 on the rails and are provided with antifriction bearings 30', the axis of the pivot being at the outer face of each of the rails.

Thus the coordinating element 9 and the upper and lower arms 10 and 11 form a door supporting bracket which will permit the door to swing as a balanced door or as a panic door in the manner later to be described.

A panic arm 31 is pivoted at 32 on a bracket 33 carried by the upper rail 1 of the door and extends along the upper face thereof between its vertical walls and is free to pass over its inner edge as the door assumes the position illustrated in Figure 16 of the drawings. A guide pin 34 is carried by this panic arm and is provided with a roller bearing at 35 which is adapted to operate in a trackway 36 that extends longitudinally of the head of the doorway. This pin 34 acts as a sliding pivot member when the door is operated as a balanced door.

A panic latch, including a bolt 37 that is normally pressed by a spring 38 into a cam notch 39 in the panic arm 31 to maintain the panic arm rigid with the door, is located within a recess in the upper face of the upper rail 1 of the door and is thus hidden from view.

With the weight of the door supported by the coordinating element 9 and the arms 10 and 11 and with the guide pin 34 located substantially midway between the stiles of the door, the wind pressure on the face of the door will offer no substantial resistance to the pivotal movement of

the door about the pin 34 when force is applied to the door between the pivot 34 and the free edge of the door. When force is thus applied to the door, the door will swing or pivot about the guide pin 34 with the result that the free edge of the door will move outwardly of the doorway and the opposite edge of the door will move inwardly at the same time that the door moves about the pivot 34, the door supporting bracket, which includes the coordinating element 9 and the upper and lower arms 10 and 11, will be swung about the axis of the coordinating element as a pivot, with the result that the door will be drawn toward the jamb 5 by movement of translation.

In order that the opening movement of the door toward the jamb 5, when the door operates as a balanced door, may be checked with a cushion action, we have provided a resilient abutment member 40 which is in the line of movement of, and adapted to be engaged by, the upper end of the guide pin 34.

In order that the door, when operated as a balanced door, may be locked in its open position, we have provided a manually operable locking means within the head which includes a lever 41 pivoted at 42, one end of this lever carrying a locking bolt 43 on a sliding pivot connection 44, and the other end being provided with a finger piece 45 which has a sliding pivot connection 46 with the lever. Both the finger piece 45 and the locking bolt 43 register with openings in the door head and are so constructed that upward pressure on the finger piece will lower the locking bolt into the path of movement of the upper rail of the door to prevent the return of the door to its closed position. The bolt 43 may be released by upward pressure thereon.

The locking bolt 43 is provided with seats 47 which are adapted, selectively, to receive a spring-pressed detent 48 to hold the locking bolt either in its locking or inoperative positions as will be readily understood.

When force is applied to the inner face of the door, on both sides of the pivot 34, to open the door as, for instance, under panic conditions, the tension of the spring 38 will be overcome and the bolt 37 will be moved out of the cam notch 39 in the panic arm 31. This action will release the guide pin 34 from the door, with the result that the door will not have a pivotal action around this pin. The door will then have only one pivot, namely, that defined by the vertical line extending through the center of the coordinating element 9. The door will then swing in a similar manner to an ordinary hinged door, having no pivotal movement about the guide pin 34, and having no movement of translation, but only a pivotal or hinged action about the axis of the coordinating element 9, and no other movement, with the result that the door will be swung into open position entirely to clear the doorway, as illustrated in Figure 16.

Thus when the door is in its closed position, as shown in Figure 13, and force is applied to one face of the door between the pivot point 34 and the free edge of the door, that is to say, when a push is applied from the inside of the door, or a pull from the outside of the door, the door will pivot about the pin 34 and, because of the pivotal attachment of the arms 10 and 11 to the door and the pivotal movement of the coordinating element 9, the guide pin 34 will slide in the trackway in the head 7 of the doorway. Thus the door will have both a pivotal

movement and a movement of translation, and as a result will move from the position shown in Figure 13 through the position shown in Figure 14, and to the final position shown in Figure 15, where one portion of the door extends inwardly of the doorway and a substantially equal portion extends outwardly of the doorway.

When, however, force is applied to the inner surface of the door on both sides of the pivot 34, as for instance when, in a panic, a crowd of persons rush for the doorway, the force applied will disconnect the panic latch from the panic arm 31, and the door will swing with the coordinating element 9 and arms 10 and 11, and on the axis of the coordinating element alone, as a pivot, passing through the dotted line position shown in Figure 16 to the position shown in full lines in Figure 16. During this swinging movement the arms 10 and 11 will move with the door since the facings 26 and 27 of the upper and lower rails 1 and 2 of the door will act as abutments for the arms.

Thus the arms 10 and 11 and the door will move as a unit with no relative pivotal movement between them.

Moreover, because of the form of and the association and relationship between the door, the jamb, the coordinating element and the arms, the door will swing entirely outwardly from the doorway, extending outward from the jamb and entirely clear of the doorway with the result that there will be no interference with the passage of persons through the doorway.

In doors of the same general class as that of the subject matter of our invention in the prior patented art, as, for instance, in the Ellison Patent 2,019,528, of November 5, 1935, when the door is moved as a panic door it must necessarily, in order to open to a serviceable degree, have a compound pivotal movement as distinguished from the simple pivotal movement of the door of our invention. That is to say, it must have pivotal movement not only about the axis of the coordinating element but also about the pivot between the ends of the arms and the door itself, as is clearly illustrated in Figure 3 of said Ellison patent, where the door is shown as having moved pivotally about both of the axes 34 and 37. In this phase of our invention we distinguish from this prior art in that when the door is swung outwardly as a panic door it has a simple pivotal movement only, about the axis of the coordinating element only rather than a compound pivotal movement about the axis of the coordinating element and also the pivots at the ends of the arms.

Thus we have created a balanced and panic door which is simple and sturdy in construction and positive in operation and which, when acting as a panic door, will entirely clear the doorway to permit passage of persons therethrough without obstruction, and one in which the operating and control mechanisms are concealed within the door and doorway structure and in which the mechanical closing device for the door is located in the floor beneath the door.

While we have described certain details of construction in the embodiment that we have selected to illustrate the invention, it must be understood that many of these details of construction may be changed, as will readily be realized by those skilled in the art, without departing from the spirit of the invention and within the scope of the claims.

We claim:

1. In a balanced and panic door construction, a door framing having a transverse trackway, a door arranged within said door framing, supporting means for said door comprising a main vertical pivot member adjacent one side edge of said door, a supporting arm mounted adjacent one of its ends on said main vertical pivot member for pivotal movement about the axis thereof, a supporting arm pivot member pivotally connecting the other end of said supporting arm and said door between the side edges of said door, interengageable abutment means on said door and said supporting arm to limit the movement of said door about said supporting arm pivot member in one direction so that said door and said supporting arm may move as a unit about said main vertical pivot member only, a slideable pivot member slideable along said trackway toward and away from said main vertical pivot member in a predetermined and guided path, means for releasably connecting said slideable pivot member to said door between said supporting arm pivot member and the side edge of said door remote from said main vertical pivot member comprising a panic arm having a releasable end connected to said slideable pivot member and pivotally connected to said door at its other end, and a latch for releasably securing said panic arm and said slideable pivot member to said door, said panic arm when released by said latch being freely pivotally movable in respect to said door, and said slideable pivot member being freely movable toward said main vertical pivot member in said

5 predetermined and guided path throughout substantially ninety degrees of movement of said door on said main vertical pivot member only, and said panic arm permitting said door to move substantially ninety degrees on its said main vertical pivot member only, when said panic arm is released by said latch.

10 2. The combination recited in claim 1 wherein said panic arm is mounted above the upper face of said door and is free to move across one edge of said face.

15 3. The combination recited in claim 1 wherein said abutment means comprises a flange on said door which is engageable with a portion of said arm.

20 4. The combination recited in claim 1 wherein means is provided for automatically locking said door in an open position at the end of its movement on said main vertical pivot only.

EDMUND PEREMI.
HENRY WEIMANN.
